UNITED STATES PATENT OFFICE.

CHARLES A. LITTLEFIELD, OF MANCHESTER, NEW HAMPSHIRE, ASSIGNOR
TO THE DUTCHER TEMPLE COMPANY, OF HOPEDALE, MASSACHUSETTS.

LOOM-TEMPLE.

SPECIFICATION forming part of Letters Patent No. 445,148, dated January 20, 1891.

Application filed June 18, 1890. Serial No. 355,842. (No model.)

To all whom it may concern:

Be it known that I, CHARLES A. LITTLEFIELD, of Manchester, county of Hillsborough, State of New Hampshire, have invented an improvement in Loom-Temples, of which the following description, in connection with the accompanying drawings, is a specification, like letters on the drawings representing like parts.

This invention has for its object the production of a novel spindle for loom-temples, the construction being such as to obviate the use of oil between the spindle and temple-roll, thus avoiding the spotting of the material being woven. The body of the spindle supporting the temple-roll has a vitreous coating or enamel applied thereto in such manner as to become a permanent part of the spindle. To aid in holding the spindle in place, one end thereof is made to enter a hole in an upright part of the temple-head, and at or near its other end the spindle has an enlargement provided with a shoulder which comes in contact with a part of the free end of the cap, thus forming a brace, the said enlargement having an ear through which is inserted a screw to confine the spindle in place, said screw entering a lug projecting from the temple-head. I have applied the vitreous material to the inner side of the enlargement or head of the spindle, to thus constitute a bearing for the end of the roll.

One part of my invention consists in a loom-temple spindle provided with an enlargement at one end and having its body coated with vitreous material to form a bearing for the temple-roll, substantially as will be described.

Another part of my invention consists in a loom-temple head having a projecting lug, combined with a spindle having an enlargement provided with an ear, the said lug and ear being connected by a screw, substantially as will be described.

Figure 1 is a top or plan view of a temple embodying my invention; Fig. 2, a cross-section thereof on line xx , Figs. 1 and 3, looking toward the left; and Fig. 3, a section in the line yy , Fig. 1.

The pod a , cap a' , upright wall a^5 , preferably cast in one piece, and the flange a^4 , con-

stitute a temple-head. The flange a^4 has suitable bolt-holes, by which to attach the temple-head to any usual working parts of a temple in the usual manner. The cap a' has cast upon its upper side an ear a^3 , provided with suitable threads to receive the bolt or screw b' , which is extended through an ear c of the enlargement or head c^2 of the spindle c' , upon which in practice may be mounted to turn any usual burr-roll e . The inner side of this enlargement c^2 is provided, as shown in Fig. 3, with a shoulder 2 , which fits the concaved interior surface of the cap, to aid in giving stiffness to the spindle. Just beyond the shoulder 2 is a shoulder 3 of smaller diameter.

The body of the spindle is coated, or has applied to it or baked thereon in the usual manner a vitreous coating, as f , which may be of any usual material, and preferably this vitreous coating is applied to the inner end of the enlargement or head c^2 and made to lap over the shoulder 3 , thus forming a bearing for one end of the roll.

I have shown the vitreous coating on the spindle as extended to the end thereof and into a bearing 10 in the upright a^5 of the head, the end of the spindle resting loosely in the said bearing.

In another application, Serial No. 355,841, filed June 18, 1890, I have claimed broadly a vitreous-coated spindle for a temple-roll.

I claim—

1. A loom-temple head having a lug a^3 projecting therefrom, combined with a spindle having an enlargement or head provided with an ear c , the said ear and lug being connected by a screw, substantially as described.

2. The loom-temple head, combined with a spindle having an enlargement or head c^2 , provided with a shoulder, as 2 , to fit the inner side of the cap, the end of the said spindle opposite the said enlargement taking a bearing in the upright wall of the temple, and a connecting device between the said spindle and head, substantially as described.

3. A loom-temple spindle provided at one end with an enlargement or head, and having its body coated with vitreous material to

form a bearing for the temple-roll, substantially as described.

4. A loom-temple spindle having an enlargement or head, the spindle and the inner 5 side of the said enlargement or head being provided with a vitreous coating, to operate substantially as described.

In testimony whereof I have signed my name to this specification in the presence of two subscribing witnesses.

CHARLES A. LITTLEFIELD.
